UNITED STATES PATENT OFFICE.

GEORGE N. JEPSON, OF WORCESTER, MASSACHUSETTS.

ABRADING-WHEEL.

1,097,758.

Specification of Letters Patent. Patented May 26, 1914.

Application filed February 24, 1908. Serial No. 417,332.

To all whom it may concern:

Be it known that I, GEORGE N. JEPSON, a citizen of the United States, residing at Worcester, in the county of Worcester and 5 Commonwealth of Massachusetts, have invented a new and useful Improvement in Abrading-Wheels, of which the following is a specification, accompanied by drawings forming a part of the same, in which—

10 Figure 1 represents a side view of an abrading wheel embodying my invention with a portion of the supporting rim broken away. Fig. 2 is a face view. Fig. 3 is a central sectional view on the line 3—3, Fig. 15 1. Fig. 4 is a face view showing a modification, and Figs. 5 and 6 are detached views of the individual abrading blocks of which the rim of the wheel is composed, showing modifications in construction.

20 Similar reference letters and figures refer to similar parts in the different views.

The object of my present invention is to provide what is known as a clearance in that 25 class of composite grinding wheels formed in part of pulverized abrading material, such as emery or corundum and the like, and united in a coherent mass by a suitable bonding material.

A difficulty frequently arises in the use 30 of wheels of this class owing to the failure of the wheel to clear itself from the detached particles from the body of the wheel or from the work operated on, which, in the operation of grinding, become embedded in the 35 face of the wheel producing a glazed surface by the action of pressure and heat, thereby greatly reducing the efficiency of the wheel. By my present invention, I obviate this difficulty by providing clearance spaces 40 at frequent intervals in the grinding surface of the wheel, into which the loosened particles may be caught and thrown out by a centrifugal force, instead of being dragged over and embedded in the grinding 45 surface of the wheel.

In the accompanying drawings I have shown my invention as embodied in that type of a grinding wheel which consists of an abrasive annulus held by a central metallic support, provided with a seat to receive the inner edge of the annulus which is preferably dovetailed and embraced by clamping lips, which securely connect the annulus and its metal support.

50 Referring to Figs. 1, 2 and 3 of the drawings 1 denotes a central circular metal sup-

port, comprising a web 2 and a hub 3 with a series of radial ribs 4, and provided with a concentric hole 5 for its attachment to a revolving arbor. The web 2 is enlarged at 5 its periphery to form a seat 6 and is provided with an oblique lip 7. Attached by bolts 8 to the web 2 is a clamping plate 9 provided with an oblique lip 10 corresponding to the lip 7. Arranged around the 10 periphery of the circular metal support are a series of abrasive blocks 11, having their inner edges dovetailed at 12 and adapted to be clamped between the lips 7 and 10 and rest upon the seat 6, which receives the 15 inward thrust of the blocks 11 when pressure is applied to the periphery of the wheel. The blocks 11 are spaced by the insertion between them of steel spacing plates 13 which are inclosed between the clamping 20 lips 7 and 10. The insertion of the spacing plates 13 between the blocks 11 provide the open clearance spaces 14, and, by slightly varying the thickness of the spacing plates 13, a solid bearing is secured between the 25 dovetailed bases of the blocks 11.

In the operation of grinding the course of any loosened particles from either the wheel or the work which are dragged along the periphery of the wheel will be interrupted 30 by the open spaces 14, allowing them to be thrown off by centrifugal force. The clearance spaces 14 are placed sufficiently near together to prevent the comminution of the loosened particles by their abrasion against 35 the surface of the wheel and the consequent glazing of the wheel. The spacing plates 13 are held from removal within the clamping lips 7 and 10, but they are short enough to enable the pressure exerted by the bolts 8 40 to be received by the dovetailed bases 12 of the abrasive blocks. The size of the blocks 11 and the thickness of the spacing plates 13 are adapted to the character of the work 45 to be performed, as well as to the character 50 of the abrasive material of which the blocks 11 are composed, as, in some cases, the clearing spaces 14 would require to be wider than in others.

In Fig. 4 I have shown a modification, 55 which consists in forming abrasive blocks 15 having their opposing sides at an oblique angle to the plane of rotation, whereby the clearance spaces 16 extend obliquely across the face of the wheel instead of at right 60 angles thereto, as shown in Fig. 2. In Fig. 5 I have shown a detached view of an abra-

sive block 17 having a dovetailed base 12 and adapted to be spaced by spacing plates 13, as already described. In addition, however, to the clearance spaces formed by spacing plates between the blocks, the block 17 is provided with a series of transverse holes 18, preferably arranged in rows concentric with the wheel.

In operation, as the wheel is worn away, 10 the outer row of holes are eventually worn into and form transverse recesses upon the face of the wheel, and, as the wheel becomes worn below the first row of holes, the second or next inner row of holes are worn into and 15 so on successively as the wheel is worn away, each successive concentric row of holes 18 in turn forming the transverse recesses on the face of the wheel, into which the loosened particles fall and are thrown into by centrifugal force.

In Fig. 6 I have shown a second modification, which consists in forming a block 19 having the dovetailed base 12, but having a series of holes 20 extending over the outer 25 face 21 toward the inner face of the block, said holes 20 being parallel to facilitate their being formed while the blocks are molded from plastic material to permit the removal of the blocks from the mold.

30 The employment of blocks or sections of this character in the formation of a peripheral abrading surface furnishes means, in addition to the slots between the adjacent sections, for preventing the glazing of the 35 peripheral abrading surface of the wheel. The loosened particles are carried into said holes 20, instead of being embedded in the

surface of the wheel, and are thrown outwardly therefrom by centrifugal force.

I claim,

1. In a grinding wheel, the combination, 40 with a central supporting section provided with peripheral clamping means, of a plurality of segmental sections in annular arrangement to provide a peripheral non-continuous abrading surface, each of said segmental sections having an inner supporting portion embraced by said clamping means, and a plurality of spacing plates, co-extensive with said inner supporting portions and 45 disposed in alternating relation therewith within said clamping means, for providing free spaces between said segmental sections outside of said clamping means.

2. In a grinding wheel, the combination, 50 with a central supporting section provided with peripheral clamping means, of a plurality of segmental sections of abrasive material forming a peripheral abrading surface, each of said sections provided with a 55 plurality of holes opening upon said surface, and each of said sections having an inner supporting portion embraced by said clamping means, and a plurality of spacing plates, co-extensive with said inner supporting sections and disposed in alternating relation 60 therewith within said clamping means, whereby to provide free spaces between the said segmental sections on the peripheral abrading surface formed thereby.

GEORGE N. JEPSON.
